Primary Examiner — Jeffrey D Asch(74) *Attorney, Agent, or Firm* — NSIP Law(57) **CLAIM**

The ornamental design for a mobile terminal, as shown and described.

DESCRIPTION

FIG. 1 is a front perspective view of a mobile terminal showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof; and,
FIG. 7 is a bottom view thereof.

The broken lines shown in the figures that are within the claimed surface, are immediately adjacent to the shaded areas, and define regions that are unshaded, represent the bounds of the claim, while all other broken lines, including the circles next to the speaker and the icons next to the function button, are directed to environment. The broken lines form no part of the claimed design.
